COOLING TANK

Maurice J. Moulthrop, Oak Park, Ill., assignor to The Creamery Package Mfg. Company, Chicago, Ill., a corporation of Illinois

Application September 6, 1956, Serial No. 42,846

Term of patent 14 years

(Cl. D23—1)

Fig. 1

Fig. 2

Fig. 3

Fig. 4

Fig. 5

Fig. 1 is a perspective view of a cooling tank showing my new design;

Fig. 2 is a back view of the cooling tank shown in Fig. 1;

Fig. 3 is a top plan view of the cooling tank shown in Fig. 1;

Fig. 4 is a left end view of the cooling tank shown in Fig. 2; and

Fig. 5 is a right end view of the cooling tank shown in Fig. 2.

The dominant features of the design are represented in full lines in the drawings.

I claim:

The ornamental design for a cooling tank, substantially as shown and described.
